DENTAL FILM PACK DISPENSERS, AND
THE LIKE

Irwin C. Rinn, Park Ridge, Ill., assignor to Rinn Corporation, Chicago, Ill., a corporation of Delaware
Filed Sept. 22, 1961, Ser. No. 140,120

3 Claims. (Cl. 221—131)

This invention relates to improvements in dental film pack dispensers, and the like. In thus using the term dental film pack as defining the type of units dispensed by the dispenser construction hereinafter illustrated and described, it will be understood that dispensers embodying the features of the present invention may also be used for the dispensing of units other than film packs, provided such other kinds of units are of size and contour acceptable to the particular dispensing unit in question; but, as will hereinafter become evident, certain of the features of the present dispensing units have been devised with especial reference to the requirements imposed by such units as dental film packs. To understand the special features of construction and use of conventional film packs I shall first refer briefly to the same, in order to better understand certain of the features of construction and use of the dispenser improvements of the present application, when such dispensers are used for the dispensing of such film packs.

A typical example of one such film pack is that shown in Letters Patent of the United States, No. 2,189,299, issued February 6, 1940, on the application of the present applicant. Such film pack includes an X-ray or short ray sensitive sheet, generally backed by a film of lead or other material substantially opaque to X-rays, both enclosed in an enclosure which is opaque, to wave lengths within the visible spectrum, but transparent to wave lengths or rays such as X-rays used during the conventional use of the film pack. Such film pack is inserted into the mouth of the patient behind the tooth or teeth to be afterwards studied by the dentist, with such lead backing at the back of the so-inserted pack. Then, by subjecting the proper area of the mouth regions to the X-rays, the desired shadow-graph will be produced on the sensitive sheet contained in such film pack.

Now it is especially noted that although such film pack includes an enclosure which is opaque to wave lengths within the visible range, such enclosure is not of itself opaque to very short wave lengths, so that if not properly and sufficiently protected against the impacts of such short wave lengths which are normally present in most daylight illuminations, some X-ray effects will find their way through the enclosure of the film pack, with consequent impairment of the quality of the enclosed sensitive film, and corresponding impairment of the sharpness and overall quality of the shadowgraph afterwards produced on the film. It is thus very important to protect the unused film packs against possible intrusion of such stray X-rays, so that even after considerable intervals of time the quality of the film packs shall not be impaired; and it is also important to continue such protection of the film packs, even after they have been intentionally exposed during the intended X-raying operation, until the development or processing of the exposed film packs has been carried out. It is a prime object of the present invention to provide for such effective protection of the film packs both before and after their intended and normal

2

use. The protection afforded against effects of stray radiation, is such that all stray radiation which might affect the sensitized film is blocked or opaqued by the shell of the dispenser, and thus does not reach any of the film packs contained in the dispenser. By way of illustration only, one successful embodiment of the present invention includes a shell of substantially one-tenth inch (0.100") thickness and formed of an alloy including or comprising steel such as medium carbon steel, hereinafter referred to.

It is also here noted that such protection against the entry of stray radiation into the dispenser, and into contact with the film packs, includes protection at such special locations, as the door through which access is provided for insertion and removal of certain of the film packs, and the removable cover which, when removed gives access to the film packs which have been exposed in intended manner to produce shadowgraphs of the patient's teeth and gums. Such protective provisions will be disclosed in detail hereinafter.

At this point it is noted that during the usual practice of the dentist or other user of such X-ray equipment, use is conventionally made of several sizes and contours of the film packs. These include such film packs as what is conventionally designated as #2 or standard size film, #1 or narrow film, and #0 or pedodontal film, as well as conventionally known and used "bite-wing" film packs, which packs include the laterally extending tab or bite-wing which is engaged between the patient's teeth during the film exposure operation, to ensure correct holding of the film pack during such exposure. It is desirable to have conveniently at hand sufficient numbers of all such (and possibly other) sizes and contours of film packs so that all possible requirements as to film pack specifications may be immediately satisfied during the various X-ray exposures to be made on a given patient, without need of delays and possible inabilities to meet all various requirements imposed by the special conditions found to exist in the mouth, teeth, and gums of such patient. It is an object of the present invention to provide a dispensing unit of such construction that provision is made for accommodating various sizes and contours of the film packs, including such bite-wing type units; and for enabling withdrawal of selected specification film packs, one at a time, from the dispenser, as needed during the successive X-raying operations. Also, to provide simple means to restore each of the exposed film packs to the interior of the X-ray impervious material container for storage under the protection of such container until such time as it may be desired to remove the exposed film packs for development and/or other subsequent treatment. Such simple means enabling restoration of the exposed films to the interior of the dispenser includes a slotted opening through which the film packs are introduced back into a deep tray within the dispenser, together with a spring closed shutter normally overlying such slotted opening.

Since the bite-wing film packs include laterally extending lugs which are gripped between the teeth during the X-ray exposing operation, it is inconvenient to dispense such special contour film packs by means of conventional finger draw slides. Accordingly, provision is made for receiving and accommodating such bite-wing units within shallow trays located within the X-ray impervious shell of the dispenser, but which trays are readily accessible

through a hinged door, normally spring closed. Such trays are also slideable outwardly through the door to a limited extent to facilitate removal of the bite-wing film packs carried by the trays. The arrangement is also one which ensures against complete removal of the trays from the dispenser, except by an intentional removing operation, thus ensuring against spillage of the film packs from the trays when the door has been opened.

The non-bite wing film packs are conveniently received and retained in several vertical chutes of conventional form, together with simple draw slides at the bottoms of such chutes, for convenient finger operation to remove the film packs from the lower ends of the stacks contained in the chutes, one at a time. Conveniently, all of the chutes (for example, three in number) are of the same size, sufficiently large to accommodate the largest specification film pack to be accommodated. Provision is then made for introduction into each of one or more such chutes of an adapter of size to seat nicely within the chute, and of construction such as to accommodate a smaller specification film pack, or a film pack of different contour from the non-adapter provided chute or chutes.

The dispenser is so constructed that it may be readily carried by suitable headed screws or expansion bolts, or the like, set into or secured to a convenient wall or other structural element.

The dispenser units hereinafter illustrated and described embody structural features complying with all of the foregoing objectives.

A further object of the invention is to provide a design of dispenser which includes various parts and elements of such nature that they may be readily produced from sheet metal and by conventional sheet metal shop operations.

Other objects and uses of the invention will appear from a detailed description of the same, which consists in the features of construction and combinations of elements hereinafter described and claimed.

In the drawings:

FIGURE 1 shows a front elevational view of one embodiment of my present invention;

FIGURE 2 shows a back view corresponding to FIGURE 1;

FIGURE 3 shows a right-hand side elevational view corresponding to FIGURES 1 and 2; and in FIGURE 3 the side door is shown closed;

FIGURE 4 shows a left-hand side elevational view corresponding to FIGURES 1, 2 and 3, but in FIGURE 4 the upper portion of the left-hand side wall has been broken away to reveal the interior construction of various elements;

FIGURE 5 shows a top plan view corresponding to FIGURES 1, 2, 3 and 4; and FIGURE 5 shows the slotted opening through which the exposed film packs may be introduced into the exposed film pack tray within the upper portion of the shell;

FIGURE 6 shows a right-hand side elevational view corresponding to FIGURE 3, but with the side door fully opened to give access to the several trays which carry un-exposed film packs, but without exposure of the film packs which have been used, to external stray radiation;

FIGURE 7 shows a vertical elevational section taken on the lines 7-7 of FIGURES 6 and 8, looking in the directions of the arrows;

FIGURE 8 shows a horizontal cross-section taken on the lines 8-8 of FIGURES 4 and 6, looking in the directions of the arrows;

FIGURE 9 shows a fragmentary view corresponding to FIGURE 7 but with the central portion of the dispenser broken away, but on enlarged scale; and FIGURE 9 may also be considered as a fragmentary vertical section taken on the lines 9-9 of FIGURES 10 and 11 looking in the directions of the arrows;

FIGURE 10 is a fragmentary vertical section taken on

the line 10-10 of FIGURE 9, looking in the direction of the arrows;

FIGURE 11 is a fragmentary horizontal section taken on the lines 11-11 of FIGURES 9 and 10, looking in the directions of the arrows;

FIGURE 12 is a fragmentary section taken on the line 12-12 of FIGURE 13, looking in the direction of the arrows; and FIGURE 12 shows an end view of the spring-closed flap or door which normally closes the slotted opening through which the exposed film packs are introduced into the storage pan or tray within the shell of the dispenser; and in this figure such flap is shown in closed position by the full lines, and in opened position by the dashed lines;

FIGURE 13 shows a view of the flap or door, taken on the line 13-13 of FIGURE 12, looking in the direction of the arrows;

FIGURE 14 shows a bottom view corresponding to FIGURES 12 and 13;

FIGURE 15 shows a fragmentary horizontal section taken on the line 15-15 of FIGURE 6, looking in the direction of the arrows, but on enlarged scale as compared to FIGURE 8; and FIGURE 15 shows a plan view of one of the "bite-wing" trays;

FIGURE 16 shows a vertical cross-section taken on the line 16-16 of FIGURE 15, looking in the direction of the arrows; and

FIGURE 17 shows a vertical longitudinal section taken on the lines 17-17 of FIGURES 15 and 16, looking in the directions of the arrows.

Since a prime objective of the present invention is to provide a container wherein the film packs may be stored prior to their intended exposure and use, with provision for facilitating the dispensing of such film packs one at a time for intended use; together with further means permitting restoration of the exposed film packs into such container to be there held under protection against damage by stray radiation during a considerable interval of time, and provision for then conveniently removing the exposed film packs for development or processing; it is evident that the shell of the container, as well as its mechanical construction, must be of material and so constituted as to prevent access of such stray radiation to the contained film packs in such quantity as to cause damage to either the unused film packs, or those film packs which have been conventionally used and exposed and stored.

The container or dispenser herein illustrated includes a substantially rectangular housing 20, including the walls 21, 22, 23 and 24, the bottom 25, and the top or removable cover 26. Such housing is made from material of characteristics and thickness to be highly absorbent of X-rays and other radiation of wave-lengths which will affect the sensitized surface of the films contained within the film packs.

The dispensers herein disclosed are designed and constructed for convenient support at or close to the location where the X-raying operations are produced from the patient's anatomy by the technician. Each film pack of desired size and/or specifications may be readily withdrawn from the dispenser by the technician or attendant, quickly inserted into the mouth of the patient, adjusted therein, and otherwise prepared for the X-ray exposure.

Thus, only that film pack is removed from the dispenser which is to be conventionally exposed immediately after such removal from the protection afforded by the dispenser. The dispenser is also provided with a normally closed slotted opening through which each exposed film pack is returned to the protected interior of the dispenser immediately after conclusion of the intended conventional exposure of such film pack. Thus the film pack is thus exposed to the intrusion of stray radiation during a time interval, with corresponding substantial improvement in the quality of the X-ray shadowgraph produced, and corresponding improvement in the quality of the technique operations.

60

65

70

The absorption of the stray radiation by the shell of the dispenser (with corresponding protection of the film packs within such dispenser, from effects of stray radiation) is an exponential function of the thickness of the shell material, as well as a function of the material from which the shell is formed. The above general rule is of course applicable in the case of radiation reaching the shell and of specified wave-length. The absorption qualities of a specified material of specified thickness, are greater in the case of the longer wave-lengths than the shorter ones. The stray radiation against which protection is to be afforded by the shell is of wave-lengths capable of penetrating the enclosure of the film-pack itself, which enclosure is of material opaque to wave-lengths within the visible spectrum. The stray radiation against which protection is to be afforded is of wave-lengths well below the visible spectrum, and deep into the ultra-violet. The foregoing conditions may be expressed by the statement that the penetrating ability of X-rays increases as the wave-length of the rays decreases (hard rays). The X-rays of larger wave-length (soft rays) contain relatively less penetrating power. The absorption of the damaging stray radiation is an exponential function of the negative exponent $(\mu/Ro)Rox$, where x designates the thickness of the absorbing medium, μ designates the linear absorption coefficient of the absorbing medium, and Ro designates the density of the absorbing medium. The ratio μ/Ro is a function of the atomic number of the absorbing chemical element and of the wave-length of the X-ray beam. The value of μ/Ro for a compound is equal to the sum of the values for each of the elements present. (McGraw-Hill Encyclopedia of Science and Technology, vol. 11, page 302, seq.)

Copper, nickel, thorium, lead, tantalum, tungsten, gold, and other rare metals or materials have a higher absorbing quality than iron; but zirconium, titanium, aluminium, boron, graphite, beryllium, and lucite and various plastic compounds, glass, and other materials, have lower absorbing qualities than iron. Since the stray radiation is generally of low intensity, except possibly close to the technical apparatus used during the X-raying operations, and since the time interval during which the film pack removed from the dispenser is within close range to the X-ray technical apparatus, being generally substantially away from such X-ray apparatus even after removal of such film pack from the dispenser, it is not necessary to make special provision against stray radiation of high intensity, but only against stray radiation of comparatively low intensity. It has been found that an iron enclosure for the dispenser, of substantially 0.100" thickness, being "soft iron," will effectively shut out all stray radiation within the X-ray range of wave-lengths generally to be encountered during X-ray technique operations wherein the film packs are used. It is also found that when the dispenser shell is formed of material substantially conforming to the absorbing qualities of such thickness of iron, all stray radiation reaching the dispenser shell even over long intervals of time, is cut-off so that the film packs may be safely stored in a dispenser having a shell substantially conforming to such X-ray absorbing qualities.

Within the shell already defined, an inverted U-shape base element, 27, is set with its flanges 28 and 29 (see FIG. 6) supported on the floor 25, thus establishing a horizontal sheet 30 slightly above the floor and extending from front to back of the shell, and with its front end set backwardly from the front plate 21 of the shell (see FIGURE 6). The top surface of this sheet 30 serves as a horizontal planar support for each of the three slides 31, 32 and 33 (see FIGS. 1, 6, 8, 9, 10 and 11) which serve the lower ends of the three chutes 34, 35 and 36 wherein the unused film packs are carried, corresponding to three specifications of size and/or contour, which chutes will be described in detail hereinafter. (See FIGURES 7 and 8, and 9, 10 and 11.)

Another U-shape plate 37, including the flanges 38 and 39, and the web 40 (see FIG. 6 and others), is set and secured above the element 27, the web 40 of such plate 37 extending vertically just behind the three chutes already referred to (see FIGS. 6, 8 and 11). Such securing of such plate 37 in such position is effected by securing the rear edge of each of the flanges 38 and 39 to the inner face of the back 23 of the shell (such securing means not being shown in detail).

The upper flange 38 of such plate 37 is located somewhat below the top of the shell, and below the cover 26; thus there is provided a space 41 in the upper rear portion of the shell, of size to accommodate numerous exposed film packs as various exposures are made (see FIG. 6). There is seated on the top surface of the upper flange 38 a thin U-shape tray 42a (see FIG. 6) having the end flanges 42 and 43; and the deep pan or open top box 44 (see FIGS. 4 and 6) is removably seated on such tray and between such end flanges 42 and 43. This box receives and accommodates the exposed film packs which are introduced into such box from time to time. Such introduction of the exposed film packs into such box is accomplished without need of removing the cover 26 from the shell. For this purpose there is provided a slotted opening 45 in the cover (see FIGS. 5, 12 and 14). Such slotted opening is normally closed by a shutter of radiation absorbing qualities substantially equal to like qualities of the shell. This shutter, 46 is flat and provided with the end flanges 47 and 48 which are pivoted to the rod 49 supported in the end flanges or lugs 50 and 51 comprising end portions of the U-shape bracket element 52 which is secured to the bottom surface of the cover 26 (see FIGS. 12, 13 and 14). The shutter element and the lugs 47 and 48 of such shutter, and 50 and 51 of the bracket element are so formed that by rocking the shutter clockwise (when viewed as in FIGURE 12) the shutter plate 46 comes into substantially flat engagement with the under surface of the cover element 26 to thus ensure good closure of the slotted opening 45 against ingress of stray radiation. The spring 53 is provided for urging the shutter to its closed position, one end of such spring bearing against the underface of the cover 26 and the other end of the spring bearing against an element of the shutter 46.

The right-hand wall of the shell is provided with a door 54 extending the full height of the unit, and hinged at its rear edge to the proximate edge of the back 23 of the shell. Such hinge is shown at 55 (see FIGURES 12, 3, 8 and 15). In order to ensure against leakage of radiation at such hinge location, I have provided the protective plate of radiation absorbent material, 56 secured to the inside surface of the door at location proximate to the hinge, and extending substantially the full height of the hinge itself. This protective plate is so formed that when the door is in closed position (see FIGURES 8 and 15) the edge of the protective plate comes substantially to the inside face of the back 23 of the shell. A spring 57 (see FIG. 15) having one end connected to the door and its other end connected to a suitable structural element of the shell, urges the door to closed position with sufficient firmness to ensure good closure. The hand grip 58 serves as a convenient element to open the door when desired. At its closed position the front edge portion of the inner surface of the door comes into engagement with the strap of radiation absorbent material 59 secured to the edge portion of the inner surface of the right-hand wall 22 of the shell (see FIGS. 3 and 8). This strap extends substantially the full height of the door and door opening, to thus intercept radiation which might enter through any crack between the shell and the closed door.

Within the shell and behind the three chutes 34, 35 and 36, I have provided two trays for accommodation of special sizes and/or contours of film packs, such as bite-wing packs, which are not conveniently delivered by conventional chute delivery arrangements. These trays are

shown at 60 and 61 in FIGURES 6, 15, 16 and 17. Each such tray is comparatively shallow for convenient removal of a film pack therefrom, when the door 54 has been opened. The tray 61 is seated on the flange 39 already referred to (see FIGURE 6) and the tray 60 is seated on a flange 62 having its front and rear edge portions connected to the web 40 and to the back wall 23 of the shell, respectively. Conveniently there is provided a sheet of thin metal 63 seated on the top surface of each of the flanges 39 and 62, so that each such tray actually sets on such thin sheet. The right-hand edges of these thin sheets are folded over and forwardly as shown in FIGURE 16 to thus provide a shallow slot at the rear edge of the corresponding shallow trays; and another thin sheet of metal is secured to the under surface of each such shallow tray at the left-hand end portion of the tray, such sheet for the tray 60 being shown in FIGURE 15, and there numbered 64. Each of such sheet (64) extends rightwardly of its tray only part of the dimension of such tray across the shell; and each such sheet 64 extends rearwardly beyond the rear edge of its tray, and is received in the shallow slot already referred to. Thus, each such shallow tray is permitted rightward withdrawal to the extent of bringing the right-hand edge of its thin sheet 64 into engagement with the hinge element 55 or the protective sheet 56, thus preventing inadvertent complete withdrawal of the tray from the shell. Such partial withdrawal is, however, sufficient to enable convenient removal of one of the film packs carried by the tray. Immediately after such removal, the tray may be restored to its full entry into the body of the shell, whereupon the door 54 may be allowed to close under spring urge.

It is also noted that each of such shallow trays may be completely removed from its engagement with the slotted engagement with the folded portion of the thin sheet 63, by raising the front portion of such tray into tilted position, and then shifting the tray forwardly far enough to permit disengagement of the projecting portion of the sheet 64 from the slotted recess. Conversely, the tray may be re-inserted into its intended engagement by reversal of such operations.

Referring again to the three chutes 34, 35 and 36, each of these includes a vertical channel element, 65, 66 and 67, for the three chutes, respectively (see FIG. 11). These channel elements are all of the same size (in the embodiment illustrated in the drawings), for reasons presently to be apparent. The flanges of these channels extend down to suitable supporting means, but the webs, 65^a, 66^a and 67^a, of the three channels terminate above such supporting means, as indicated by the lines 65^b, 66^b and 67^b (see FIGURES 9 and 10). Thus there is provided a clear open space at the lower rear portion of each such channel, through which space the draw delivery slide corresponding to such channel extends and operates. Conveniently the lower ends of the flanges of the channels 65, 66 and 67 rest on rearwardly extending metal strips 68, 69, 70 and 71 which are set onto the top face of the element 27 already referred to (see FIG. 9). Such strips may be secured in such position in convenient manner.

Between the strips 68-69, 69-70, and 70-71 there are located the draw delivery slide bars or plates 33, 32 and 31, respectively. These plates extend forwardly through slotted openings 82, 83 and 84 in the front 21 of the shell; and the finger grips 75, 76 and 77 are secured to the front ends of such plates 33, 32 and 31, respectively. Each such plate extends rearwardly into the space below the flange 39 of the element 37 (see FIGURE 6), and the rear end portion of such plate carries on upstanding abutment, as shown at 78 (see FIGURES 6 and 8). Each such abutment is of height sufficient to prevent withdrawal of the slide plate forwardly for complete removal of such slide plate from its working position. To this end each such abutment is of height sufficient to engage the inner surface of the front wall 21 just above the slotted opening in such front wall, through which slotted

opening the slide plate extends for connection to the finger piece 75, 76 or 77, as the case may be. Such slotted openings in the front wall 21 will be further considered hereinafter. By raising the front end portion of such plate (as by insertion of the finger below the gripping element 75, 76 or 77, as the case may be), it is possible to turn the abutment into a more or less horizontal position, thus permitting complete withdrawal of the slide plate from the unit.

10 Each such draw delivery slide plate has secured to its top surface an upwardly extending block 72^a, 73^a, or 74^a, as the case may be (see FIGS. 6, 8 and 11). Such block is of sufficient height to engage the rear edge of the lowermost film pack of a stack of film packs carried within 15 the channel 65, 66 or 67, as the case may be; but such block is not of sufficient height to engage the next higher film pack, so that delivery is made of only a single film pack at each forward draw of such plate 33, 32 or 31. It is also noted that the elevation of the lower end 65^b, 20 66^b or 67^b of the web of the corresponding channel, is sufficient to permit free passage of such block 72^a, 73^a or 74^a, as the case may be beneath such lower end 65^b, 66^b or 67^b, as the case may be (see FIG. 9); it being understood that such blocks 72^a, 73^a and 74^a stand rearwardly of the film packs carried within the channels, when 25 the slide plates have been restored to their normal or fully rearward positions, with the finger gripping elements engaged against the front wall 21 of the shell. Also each such block is of less height than the corresponding abutment, so that its block may move through the corresponding slotted opening of the front wall 21 to produce full 30 delivery of the film pack being delivered by such slide plate, it being noted that each block 74 is of less height than the corresponding abutment (see FIG. 6). The operation of delivery of the film pack will be further explained hereinafter.

Examination of FIGURES 7, 9 and 11 shows that such slide plates are of width to extend between the pairs of strips 68-69, 69-70, and 70-71, respectively, so that the back and forth sliding movements of such slide plates are well guided.

The film packs are stacked within the channels 34, 35 and 36 by introduction at the tops thereof; but I have provided "channel adapters" which are set directly into the several channels, and into which the film packs are then stacked; such channel adapters being indicated at 79, 80 and 81 in the three channels 65, 66 and 67, respectively. These channel adapters may be of size and contours to accommodate film packs all of the same specifications; or, as shown in FIGURES 7, 8, 9 and 11 the channel adapters for the several channels may be of specifications to accommodate different sizes and contours of the film packs. It is noted, however, that since all of the channels 65, 66 and 67 are of the same dimensions, the several channel adapters may be used interchangeably in such several channels, 65, 66 and 67. Thus, as shown, the adapter 79 set into the channel 65 accommodates film packs of full size conventionally known as #2 Standard, the adapter set into the channel 66 accommodates film packs of shallow depth but full width, conventionally known as #1 Narrow Film, and the adapter set into the channel 67 accommodates film packs known as Rinn #0 Pedo. The arrangement of channels oversize as compared to any of the several sizes of film packs, together with the use of channel adapters set into such channels, makes it possible for the user to accommodate a single dispenser, provided with a plurality of the master channels all of the same size and contour, to the specific needs or probable needs of his practice, or to change the adapters from time to time, to meet changing needs of his practice. For example, by providing the owner of the dispenser with adapters of the form shown in FIGURES 7, 8, 9 and 11, together with an extra adapter of the form shown at 79 (being a full size film pack adapter) the owner and user 75 of such dispenser is able to meet customary requirements

of sizes and contours of film packs, or on occasion to make provision for a double number of the larger size film packs, by substituting an extra adapter of the full size specifications, in place of an adapter previously in use.

Each of the adapters includes the two lateral vertically extending shallow channels 79^a and 79^b, 80^a and 80^b, and 81^a and 81^b, for the respective adapters 79, 80 and 81. These adapter channels are provided with inwardly extending flanges 79^c and 79^d, and 80^c and 80^d, and 81^c and 81^d, respectively, at their lower ends, but the upper ends of such adapter channels are clear and unobstructed, so that the film packs may be readily set down into the various adapters between their adapter channels, with the lowermost such film pack resting on the flanges 79^c and 79^d, or 80^c and 80^d, or 81^c and 81^d, as the case may be. The forward vertical flanges of the two channels 79^a and 79^b, 80^a and 80^b, and 81^a and 81^b, of the several adapters are provided, just above the bottom flanges 79^c and 79^d, and 80^c and 80^d, and 81^c and 81^d of such channels, with the slots 79^e and 79^f, 80^e and 80^f, and 81^e and 81^f, (see FIGURES 7 and 9). These slots are of lateral dimension to permit forward sliding delivery of the film pack resting on the bottom flanges 79^c and 79^d, 80^c and 80^d, or 81^c and 81^d, as the case may be, as the slide plate 33, 32 or 31 is drawn forward, thus drawing its block 72^a, 73^a or 74^a forward and against the said lowermost film pack. The slotted openings in the front of the shell, through which the slide bars or plates 33, 32 and 31 extend (being numbered 82, 83 and 84, respectively) (see FIGURE 1), are of vertical dimension sufficient to permit such delivery of the lowermost film pack through the front wall of the shell far enough to enable the user to remove the film pack from the top surface of the slide bar on which such film pack is now resting. Then, by pressing the slide bar or plate backwardly its full permitted movement, another film pack will drop down on the flanges 79^c and 79^d, or 80^c and 80^d, or 81^c and 81^d, as the case may be, slightly above the corresponding slide plate, preparatory to executing the next delivering operation. It is here noted that the front to rear dimension of each of the blocks 72^a, 73^a and 74^a is sufficient to ensure that as each film pack is delivered by forward pull of the slide bar or plate, the block 72^a, 73^a, or 74^a, as the case may be will ride beneath the next higher film pack of the stack being acted upon, and will thus serve to support such stack until such slide bar or plate is purposely returned rearwardly to its normal position; whereupon the stack of film packs in question may descend slightly, bringing the now lowermost film pack onto the flanges 79^c and 79^d, or 80^c and 80^d, or 81^c and 81^d, as the case may be, preparatory to execution of the next film pack delivering operation.

It is now noted that the lateral edge portions of the lowermost film pack rest on the side flanges 79^c and 79^d, or 80^c and 80^d, or 81^c and 81^d, as the case may be so that such lowermost film pack does not rest on the slide plate as long as the slide plate remains in its rearward position. Then, as the slide plate is drawn forward to deliver a film pack the lateral edge portions of such lowermost film pack are supported by said flanges 79, 80 or 81, as the case may be, and slide on said flanges as the block 72^a, or 73^a, or 74^a as the case may be, is drawn forward, thus advancing such lowermost film pack; and the edge portions of such film pack advance through the slots 79^e and 79^f, or 80^e and 80^f, or 81^e and 81^f, as the case may be, to and through the slotted delivery opening 82, or 83, or 84, of the front 21. The lower surface of the lowermost film pack is above the surface of the slide plate an amount dependent on the thickness of the flanges 79^c and 79^d, or 80^c and 80^d, or 81^c and 81^d, as the case may be. As the delivering operation continues the rear portions of the side edges of the lowermost film pack will emerge from such slots and the film pack will be allowed to descend and rest completely on the slide plate; but such film pack

will be in advance of the corresponding block 72 or 73 or 74, as the case may be.

Referring to FIGURES 9, 10 and 11, the details of the three adapter channels are there shown. Thus, the adapter channel 79 includes the plate 85 to which the rear flanges of the channels 79^a and 79^b are secured, such plate 85 being of the full width of the channel 65 so that good lateral support for the adapter is provided when inserted into one of the channels 65, 66 or 67; and the adapter channels are secured to the vertical edge portions of such plate 85 so that full size film packs may be accommodated between such adapter channels. The adapter channel unit 80 includes the U-shape vertical element 86 whose side flanges are spaced apart the proper distance to receive and support the adapter channels 80^a and 80^b at separation correct to provide width to accommodate the smaller size film packs, which, however, includes one dimension the same as the width of the full size film packs which are accommodated by the adapter 79. Thus the smaller size film packs are accommodated between the adapter channels 80^a and 80^b, and in front of the element 86. The adapter channel unit 81 includes the plate 87 which is the full width of channel 67 so that good lateral support for the adapter is provided when inserted into one of the channels 65, 66 or 67. Then the rear flanges of the adapter channels 81^a and 81^b are secured to the front face of such plate 87 at spacing to receive and accommodate film packs which are of the same dimension as the full size film packs, in one direction, but narrower than such full size film packs.

From the foregoing descriptions of the several adapters it is seen that a larger number of sizes and contours of adapters may be designed and produced, each of which will be accommodated within a selected one of the channels 65, 66 or 67, to meet a wide range of film pack specifications.

Examination of FIGURES 4, 6, 7, 9 and 10 will reveal that the several adapters are of greater height than the channels into which they are inserted. This arrangement ensures that the top portions of such adapters may be readily grasped without interference from the corresponding channels 65, 66 or 67, during insertion and removal of the adapters, from time to time.

Examination of FIGURES 3, 6 and 8 shows that the side door 54 which gives access to the trays, does not expose the full front to back dimension of the film pack chutes, so that, in fact, only the rear portions of such chutes are exposed to stray radiation whenever such door is momentarily opened for extraction of one of the film packs from a tray. It is also noticed, from examination of FIGURES 8 and 11, that when such door is thus momentarily opened, the structural arrangements of the several film pack chute elements, including the several adapters, are such that stray radiation thus momentarily finding entrance through the opened door, would have to pass through two or three thicknesses of the vertical channels of the chutes, so that a practically perfect seal against intrusion of such stray radiation is provided even when such door is opened.

Conveniently the bottom plate 25 may be welded to the lower edge portions of the front, back and side walls of the shell. It is also desirable to form the front, 21, left and right side walls, 24 and 22, respectively, and the back wall 23 from a single integral blank of sheet metal, folded at the proper locations to produce the vertical edges of the shell. The top or cover plate comprises a sheet of proper size; and preferably the angle element 88 is secured around the bottom face of such cover sheet, set inwardly from the edge of the cover sheet a distance equal to the thickness of the sheet comprising the body of the shell, so that when the cover is set into place it will be properly anchored in position. Conveniently the door 54 is provided with the hand grip 58, already referred to; and the cover 26 is provided with the hand grip 89. The shutter 46 which normally underlies and closes the slotted

opening of the cover under spring urge, may be momentarily depressed against the urge of such spring by depression of the button 90 which includes a stem extending through the cover plate into position to engage the shutter for rock of the same into position such as shown by the dashed line in FIGURE 12.

Again considering the composition of the shell of the dispenser, with regard to the absorption qualities for absorption of X-rays, the following tabulation of most of the elements previously referred to, showing their atomic numbers and atomic weights is given, as follows:

Thorium.....	Th	90	232.05
Lead.....	Pb	82	207.21
Gold.....	Au	79	197.00
Tungsten.....	W	74	183.86
Tantalum.....	Te	73	180.95
Copper.....	Cu	29	63.54
Nickel.....	Ni	28	58.71
Iron.....	Fe	26	55.85
Titanium.....	Ti	22	47.90
Aluminium.....	Al	13	26.98
Graphite.....	C	6	12.011
Boron.....	B	5	10.82
Beryllium.....	Be	4	9.013

This tabulation shows that iron, which is about midway of the listed elements, both as respects atomic number and atomic weight, also occupies a central position within such listing, as respects its absorption qualities for absorption of the X-rays, especially the stray radiation against which the present dispenser is qualified to protect the film packs. Iron also possesses the great advantages of low cost, commercial availability in quantities, wide distribution, and, when alloyed with other elements and/or materials, of being substantially rust proof and stable against the elements. It is to be understood, however, that I do not intend to limit the protection to be afforded by the present application, and the claims, except as I may limit myself in such claims; but I also contemplate the use, in such dispensers, of other materials having substantially the absorption qualities of iron.

It will be understood that when in use a control weight of conventional form may be set onto the top of each stack of film packs carried by the chutes, such weights being of size, weight, and contour to meet the requirements of the several chutes and their stacked contents.

In FIGURE 2 I have shown the two vertically aligned "key" openings 91, which may be set onto suitable headed studs projecting from the supporting element, according to conventional practice.

Examination of FIGURES 1 and 10 shows that each of the openings 82, 83 and 84 which extend through the front wall 21 of the shell, and through which openings the slide plates 33, 32 and 31, respectively, operate, are of height greater than such slide plate thicknesses, in order to accommodate the film packs carried by the slide plates during delivery movement of such plates, and to permit the film packs to be delivered to the exterior of the shell. Such excess height of such openings 82, 83 and 84 would not be sealed by the slide plates against entrance of stray X-radiation to the interior of the shell, and thus would constitute a hazard to the continued protection of the film packs contained within the shell. In order to protect against such hazard I have provided the double thickness wings 92, 93 and 94 (see FIGURES 1, 3, 4 and 10) carried by the slide plates directly behind the finger grips 75, 76 and 77 by which such slide plates are moved, such wings being so formed and located with respect to the slide plates and the finger grips, that when the slide plates are moved back to the rearmost positions at which the lowermost film packs descend to carrying engagement by such slide plates, such wings seal tightly against the outside surface of the front of the shell, thus effectively protecting against ingress of stray radiation during the considerable intervals of time that the dispenser is not

being used. In connection with the above, the finger grips 75, 76 and 77 by which the slide plates are operated, extend outwardly at elevation higher than the slide plates themselves (see FIGURES 1, 4 and 10). The wings 92, 93 and 94 then extend down from said finger grips far enough to completely seal the slide openings through which the film packs are drawn, so that the desired closure and sealing of said openings against stray X-radiation is produced when the slides (and the wings) are pushed back into their closed position.

I claim:

1. A dispenser for dispensing substantially flat film packs which comprise photosensitive sheets enclosed in flat envelopes of material opaque to wave lengths in the visible spectrum but transparent to X-radiation, said dispenser including a vertical channel element open at its lower end and comprising a vertical chute of size and contour to receive in telescoping fashion a vertical adapter to accommodate a vertical stack of film packs lying horizontal and flat on each other, means to support the lower ends of the side flanges of said channel element, the lower end of the web of the channel element being at an elevation higher than the supported lower ends of the side flanges of said vertical channel element to provide a first defined opening beneath the lower end of the web and between the side flanges of such channel element with the top of said opening higher than the supported lower ends of the side flanges of such channel element; a shell enclosing said chute and composed of material substantially opaque to stray X-radiation, a horizontal slotted second defined opening in the shell in horizontal alignment with the first defined opening, a horizontally movable slide element extending through the second defined opening of the shell and movable through said first defined opening, the slide element being of length such that when it is moved inwardly to bring its outer end in proximity to the second defined opening, the inner end of such slide element extends through the first defined opening to a position rearward of said opening; a U-shaped adapter of size and contour to telescopingly seat into the chute aforesaid, said adapter comprising a pair of shallow vertical channels in proximity to the opposing surfaces of the chute and with the front edge flanges of said shallow channels lying in a common vertical plane and constituting vertical abutments to define the front vertical corners of the stack of film packs accommodated within such adapter, and a vertical plate extending between said vertical channels to define the rear vertical enclosure for the stack of film packs accommodated within such adapter; horizontal flanges connected to the lower ends of the webs of the shallow vertical channels of the adapter and extending towards each other and providing lateral edge supports for the stack of film packs within such adapter, the lower ends of the front edge flanges of the shallow adapter channels being located at elevations high enough to permit horizontal delivery movement of the lowermost film pack, produced by out movement of the slide element; together with an upwardly extending film pack driving block secured to the slide element and of vertical dimension to engage against the rear edge of the lowermost film pack of the stack, the first defined opening being of vertical dimension sufficient to allow the film pack driving block to move through said first defined opening during back and forth movements of the slide element.

2. A dispenser as defined in claim 1, wherein there is a plurality of said vertical channel elements all of equal cross-sectional area and contour; and wherein there is an adapter telescoped into each of the vertical channel elements, each such adapter being constituted to receive a stack of film packs of selected cross-sectional area and contour corresponding to the cross-sectional area and contour of such adapter.

3. A dispenser as defined in claim 2, wherein the adapters are of selected different cross-sectional areas and contours.
